UNITED STATES PATENT OFFICE.

LYLE K. SNELL, OF DETROIT, MICHIGAN, ASSIGNOR TO CADILLAC MOTOR CAR COMPANY, OF DETROIT, MICHIGAN, A CORPORATION OF MICHIGAN.

HOOD CONSTRUCTION.

1,226,269.

Specification of Letters Patent. Patented May 15, 1917.

Application filed April 8, 1915. Serial No. 20,088.

To all whom it may concern:

Be it known that I, LYLE K. SNELL, a citizen of the United States, residing at Detroit, in the county of Wayne and State of Michigan, have invented a new and useful Hood Construction, of which the following is a specification.

The present invention relates to hood constructions for motor vehicles, and its object 10 is to provide means for forming an exit passage along the lower edges of the sides of the hood, whereby free circulation of the air is insured. Another object is to provide very cheaply means for protecting the wires 15 by which the current is brought to the headlight.

The nature of the invention will be more fully understood from the following description and the drawings wherein one embodiment is shown, and in which Figure 1 is a side view, parts being broken away. Fig. 2 is a vertical transverse section. Fig. 3 is a fragmentary plan view, parts being broken away, showing the relation of the electric headlight wires to the member for forming the air passage. Fig. 4 is an enlarged transverse section of the member showing the wires in position.

Similar reference characters refer to like parts throughout the several views.

In the embodiment of my invention shown, the upper sections 1 and 2 of the hood are joined by a longitudinal pivot rod 3 that allows either section to be swung upwardly about the edge of the other; and to the edges of the upper sections the side sections 4 and 5 are attached by pivot rods 6 and 7, the latter allowing inward swinging movement of the side sections about the edges of the upper sections. The hood may be supported at its front end upon a transverse flange 8 of the proper contour carried by a radiator 9, and at its rear end upon a similar transverse flange 10 carried by the lash 11, or in any other desired manner, apes 12 of fabric or similar material being interposed to prevent rattling. The general construction thus far described is well known.

The usual longitudinal side bars are indicated at 15. Mounted upon the upper flange of the side bars and spaced therefrom by filler blocks or plates 16 are pressed metal plates, each of which preferably includes a horizontal flange 18 (through which the

screws 19 pass whereby the plates and the fillers are secured to the side bars) and a vertical flange 20. The latter is spaced somewhat interiorly from the lower edges of the side sections to prevent water from obtaining access to the space beneath the hood, and the flange 18 is also spaced from the hood and preferably passes outwardly beyond the plane of the side section thereof, whereby a passage 21 is formed through which heated air may escape as indicated by the arrows. The side sections may, if desired, be provided with the usual louvers 22, and are retained in place by the usual spring clamps 23 and hooks 24. For convenience 76 of attachment, the dust guards 25 may have their edges inserted between the side bars and the filler plates and secured in position by the screws 19.

The outer edge of the flange 18 is preferably bent to form a conduit 26 that may close the space between the main portion of the flange and the side bar, and which may extend forward of the radiator, whereas the vertical flange 20 and a portion of the flange 18 may terminate at the inner face of the radiator (Fig. 3). This conduit may be utilized for concealing and protecting the usual wires or cable 28 whereby current is brought to the headlight 29, thus dispensing 85 with the ordinary cable armor. The cable may pass out the rear end of the conduit or laterally beneath the flange 18 at a point 30 forward of the dash and is connected to any suitable current source. 90

The space between the side bars is, of course, closed in the usual manner (not shown).

The details of the construction may obviously be varied considerably without departing from the spirit of my invention. I do not, therefore, wish to be limited otherwise than as indicated by the subjoined claims.

I claim:—

1. In combination, a motor vehicle having a hood including a top section and a side section pivotally connected thereto and means for normally forming a narrow passage along the lower side edge of the side section through which heated air may escape. 100

2. In combination a motor vehicle having a hood including a top section and a side section pivotally connected thereto and 110

means for normally forming a narrow passage along the lower side edge of the side section through which heated air may escape, the exterior opening to said passage being entirely beneath the corresponding lower edge of the hood.

3. In combination, a motor vehicle including side bars and a hood having its lower edges arranged above said side bars, 10 a plate carried by each of the side bars and extending upwardly therefrom, said plate being spaced apart and within the corresponding side of the hood, whereby a passage is formed for the escape of heated air 15 from beneath the hood.

4. In combination, a motor vehicle including side bars and a hood, a plate carried by each of the side bars, said plate including a flange that extends horizontally beneath the corresponding edge of the hood in spaced relation thereto and a vertical flange that rises from the horizontal flange and is also spaced from the edge of the hood, whereby a passage is formed for the 25 escape of heated air from beneath the hood.

5. In combination, a motor vehicle including side bars and a hood, a plate carried by each of the side bars, said plate including a flange that extends horizontally beneath 30 the corresponding edge of the hood in spaced relation thereto and a vertical flange that rises from the horizontal flange and is also spaced from the edge of the hood, whereby a passage is formed for the escape of heated air from beneath the hood, one of the flanges being shaped to form a longitudinally extending conduit, a headlight, and a cable within said conduit for conducting electricity to said headlight.

40 6. In combination, a motor vehicle including side bars and a hood, a plate carried by each of the side bars, said plate including a flange that extends horizontally beneath the corresponding edge of the hood in spaced relation thereto and a vertical flange that rises from the horizontal flange and is also spaced from the edge of the hood, whereby a passage is formed for the escape of heated air from beneath the hood, means for spacing the main portion of the horizontal flanges from the corresponding side bars, said horizontal flanges being shaped to form conduits that close the spaces between the side bars and the main portions 45 of the horizontal flanges, a headlight, and a cable within said conduit for conducting electricity to said headlight.

7. In combination, a motor vehicle including side bars and a sectional hood, said 50 hood being arranged to be opened and closed and means for supporting said hood in such position that its side edges are some-

what above the side bars, whereby unobstructed passages are formed for the escape of heated air beneath the lower edges of the 65 sides of the hood when said hood is closed.

8. In combination, a motor vehicle including side bars and a hood, means for supporting said hood in such position that its side edges are somewhat above the side bars, 70 whereby unobstructed passages are formed for the escape of heated air beneath the lower edges of the sides of the hood, and means for preventing water from entering the interior of the hood through the air 75 passages.

9. In combination, a motor vehicle including side bars and a hood, means for supporting said hood in such position that its side edges are somewhat above the side 80 bars, whereby unobstructed passages are formed for the escape of heated air beneath the lower edges of the sides of the hood, and a deflector plate arranged in said 85 passages.

10. In combination, a motor vehicle having a hood including a top section and a side section pivotally connected thereto, means for normally forming a narrow passage along the lower side edge of the side 90 section through which heated air may escape, and resilient means for holding the side section in proper relation to the passage and for preventing rattling.

11. In combination, a motor vehicle having a hood including a top section and a side section pivotally connected thereto, means for normally forming a narrow passage along the lower side edge of the side section through which heated air may escape, the exterior opening to said passage 100 being entirely beneath the corresponding lower edge of the hood.

12. In combination, a motor vehicle having side bars and a sectional hood, said hood being adapted to be opened and closed, and means concealed by the hood for supporting the latter in such position that its side edges are somewhat above the side bars whereby narrow unobstructed passages are formed 105 for the escape of heated air beneath the lower edges of the sides of the hood when said hood is closed, and tension means whereby the side edges of the hood are held down in proper relation to the side bars and 110 whereby rattling is avoided.

In testimony whereof I sign this specification in the presence of two subscribing witnesses.

LYLE K. SNELL.
